UNITED STATES PATENT OFFICE.

ALICE KOMROSKY, OF VALLEY CITY, NORTH DAKOTA.

MAIL-BOX.

1,261,037.

Specification of Letters Patent. Patented Apr. 2, 1918.

Application filed October 7, 1915. Serial No. 54,614.

To all whom it may concern:

Be it known that I, ALICE KOMROSKY, a citizen of the United States, residing at Valley City, in the county of Barnes and State of North Dakota, have invented certain new and useful Improvements in Mail-Boxes, of which the following is a specification.

My invention relates to the class of deposit and collection receptacles and more particularly to a mail receptacle having an improved cover, and a signal associated therewith. I have also provided a shelf which may be used by persons desiring to address mail at the receptacle.

The invention has for one of its principal objects the provision of a mail box which is simple in construction and durable, and cheap to manufacture.

With the above and other objects in view my invention resides preferably in the construction, combination and arrangement of parts as hereinafter set forth in the specification as illustrated in the accompanying drawing, in which—

Figure 1 is an end elevation of a mail box embodying improvements of my invention,

Fig. 2 is a front side elevation of the same,

Fig. 3 is a transverse sectional view taken on the line 3—3 of Fig. 2 looking in the direction of the arrows,

Fig. 4 is an end elevation of said mail box looking in the direction opposite to that of Fig. 1 with part thereof broken away, and

Fig. 5 is a detail perspective view showing a portion of the invention.

Similar reference characters designate similar parts throughout the various views of the drawing.

In the drawing, wherein the preferred embodiment of my invention is illustrated I have shown a receptacle 1 having a rear wall 2, curved top wall 3, provided with an opening 4 and a bottom wall 5. End walls 6 and 7 are also provided.

I have provided a suitable closure for the opening 4 embodying an elongated arcuate plate 8 carried on arms 9 pivoted at 10 to the end walls of the receptacle 1. As shown to advantage in Fig. 2, a partition 11 is provided in the interior of said receptacle, thereby affording different sized compartments. A suitable receptacle 12 is carried on the wall 11 in which coin or cur-

rency may be placed for stamps or the like. An ordinary hasp 13 is pivotally carried by the free extremity of the closure 8 and is adapted to be connected over the loop 14 mounted on the base of the front of the receptacle.

I have provided an improved signal, said signal including an arm 15 pivoted at 16 to the end wall 7, said arm having a right angularly extending portion 17 formed thereon. The arm 17 is receivable and adapted for movement under a spring strip 18 fastened adjacent its alined, opposite extremities 19 to the end wall 7. The spring 70 strip 18 is shown to advantage in Fig. 5 and it will be noted that said strip is formed with two off-set portions 20 adjacent its opposite extremities, said off-set portions being adapted to receive and retain the arm 15 at the end of each movement thereof. An enlarged portion 21 is carried by the arm 15 and serves as a signal.

One of the end walls, preferably the end wall 6, is provided with an elongated opening 22 in which letters or small mail matter may be deposited. A closure 23 is provided said closure being pivoted at 24 and adapted to be swung over said opening 22. A stop 25 is provided for said closure.

I have also provided a shelf capable for use to direct letters and the like at the mail box, said shelf being designated 26, slidably mounted in guides 27 and having the inner extremity 28 thereof provided with a stop to prevent its entire withdrawal. A handle 29 is mounted on the outer free extremity of said shelf for an obvious purpose.

Attention is directed to the peculiar arrangement of the mail box, the receiving of large and small mail matter being facilitated by the provision of large and small compartments.

It is, of course, to be understood that while a specific structure has been described and shown, I do not desire to be limited to this structure and reserve the right to make changes which are within scope of the invention as claimed.

I claim—

1. In a device of the class described, the combination of a support, a resilient retaining strip comprising a central depressed portion having end extremities in alinement therewith, said end extremities being mounted upon said support, off-set feet por-

tions formed upon said strip and being separated by the central depressed portion thereof, said feet portions extending outwardly beyond the plane of the central depressed portions and the alined end extremities, a movable arm mounted upon said support and projecting between said strip and said support, said arm being adapted to normally fit within one of said portions, 10 thus holding the arm in a set position, said arm being capable of being swung to the remaining portion by the outward swinging movement of the central depressed portion of the retaining strip, and the end extremities of said strip preventing the displacement of said arm.

2. In a device of the class described, the combination of a mail box, a signal having a straight arm depending therefrom and 20 terminating in a projection extending at right angles thereto, means passing through the junction of the arm and the angular projection thereof for pivotally supporting said arm upon a mail box, a resilient retaining strip comprising a central depressed

portion having extremities in alinement therewith, thus forming off-set retaining feet, formed out of alinement with said portion and the extremities, said extremities being fixedly mounted on said mail box, the angular projection of said arm projecting between said strip and said mail box, said angular projection being adapted to normally fit within one of the feet, thus holding the signal and arm in a set position, 35 said projection being adapted to be swung for swinging said signal and arm, thus causing the central depressed portion of the strip to be swung outwardly for accommodating the movement of the angular projection, and the secured extremities of said strip holding said angular projection and said signal arm against displacement.

40 In testimony whereof I affix my signature in presence of two witnesses.

ALICE KOMROSKY.
